UNITED STATES PATENT OFFICE.

EDWARD J. SHEEHAN, OF NEW YORK, N. Y., ASSIGNOR TO THE NOISELESS TYPE-
WRITER COMPANY, OF MIDDLETOWN, CONNECTICUT, A CORPORATION OF CON-
NECTICUT.

SHIPPING-BOX.

1,199,311.

Specification of Letters Patent. Patented Sept. 26, 1916.

Application filed February 4, 1913. Serial No. 746,106.

To all whom it may concern:

Be it known that I, EDWARD J. SHEEHAN, a citizen of the United States, residing at New York, in the county of New York and 5 State of New York, have invented certain new and useful Improvements in Shipping-Boxes, of which the following is a full, clear, and exact description, such as will enable others skilled in the art to which it 10 appertains to make and use the same.

This invention relates to boxes, and, with regard to certain more specific features thereof, to boxes especially adapted for shipping and storing fragile and delicate 15 merchandise and machines, such as typewriters, cash-registers, and the like.

One of the objects of the present invention is to provide a strong and durable box of the above character of practical construction.

Another object is to provide a simple and inexpensive shipping box adapted to yieldingly support the article or machine contained therein.

Other objects will be in part obvious and in part pointed out hereinafter.

The invention accordingly consists in the features of construction, combinations of elements and arrangement of parts which will 30 be exemplified in the construction herein-
after set forth, and the scope of the application of which will be indicated in the following claim.

In the accompanying drawings wherein 35 is shown one of the various possible embodiments of this invention, Figure 1 is a perspective view of the complete box in inverted position, with the interior parts thereof designated by dotted lines, and Fig. 2 is a 40 sectional view taken on the line X—X of Fig. 1, showing the box right side up.

Similar reference characters refer to similar parts throughout both views of the drawing.

Referring now in detail to the drawing, Fig. 1 shows a complete box in inverted position particularly designed for shipping typewriting machines. To the opposite sides 3 and 4 of the box are secured cleats 50 or strips 5 nominally positioned vertically at each end of each side and extending slightly above and below the upper and lower edges thereof in order to overlap bottom and top members 6 and 7, respectively. 55 These members 6 and 7 also extend beyond

the ends of the sides 3 and 4, in order to overlap end walls 8 and 10. It will thus be seen that when the parts are assembled each of the six surfaces of the box overlaps and is overlapped by, two adjacent opposite sides, that is, by considering the sides 3 and 4 with the attached cleats 5 as being one part, or wall. In this manner a very strong and durable box is produced which practically prevents one of the surfaces or sides 60 from breaking away from the adjacent sides by force exerted from the interior in any one direction. For example, if the securing means, either nails or screws, pass downwardly through the bottom 6 into the end 70 wall 8, as well as through the end wall into the sides or cleats 5, there are thus produced two sets of fastening means which require forces exerted at right angles in order to produce their removal. Thus this with 75 overlapping sides is particularly adapted to resist the movement in any direction of the support and the heavy machine carried thereby.

Positioned and secured in each interior corner of the box and resting upon the bottom 6, when the box is right side up, are corner pieces 11 which extend substantially two-thirds of the interior height of the box. These corner members are adapted to support a carrier hereinafter termed a skid to which the machine is secured, as will be more fully described hereinafter. This skid comprises a relatively flat board or plate 12, having at each end thereof a transverse 80 strengthening member 13 to prevent warping or splitting of the board. On the exposed surface of each member 13 and the under side of the board 12 at each end are springs 14, preferably made of sheet metal 90 and provided with upturned ends 15, as such construction is believed to be stronger and more reliable in use. These springs are secured to the skid by means of bolts 16, passing therethrough as shown. It will thus be 95 seen that these springs provide a resilient support for the machine when mounted thereon and are adapted to cushion any shock exerted in a vertical direction.

The corners of the members 13 are beveled 105 as at 17, to provide a relatively broad surface for engaging buffers 18, of rubber or other resilient material, secured in each corner of the box adjacent the end of the corner pieces 11. These buffers are adapted to 110

cushion any movement of the skid in any direction in a substantially horizontal plane. The sets of springs combined with these buffers will cushion the movement of the skid in any and all directions. Thus if the box should be dropped and land on one corner the shock will be taken up by both the springs and the corner buffers. A convenient method of using a box of this character, 10 as when shipping typewriting machines or cash-registers, is substantially as follows: The cover 7 is taken off while the box is in upright position and the skid bodily removed and placed on the upper surface of a 15 frame or table, say four or five feet high, having an opening in the under side. The machine to be shipped is then placed upon the upper surface of the skid and screws 20 or other fastening means, are inserted 20 through holes 21 directly into the legs of the machine which are preferably provided with tapped out recesses for the reception of such securing means. This manner of securing the machine to the skid lessens the 25 chances of marring the frame by external fastening means. After securely fastening the machine to the skid, the heads of screws 20 are preferably sealed over to prevent accidental removal thereof, and the skid and 30 machine are removed from the table, inverted, and lowered through the open top of the box until the upturned ends of the springs 15 coat with the four corner pieces. The cover 7 is then secured to the box, preferably by screws which are more easy to 35 remove, and in so doing the springs are slightly compressed, thus preventing any play between the springs and the cover or corner pieces that might otherwise occur. 40 The address of the consignee and directions for opening the box are then placed upon the cover to insure the box being kept right side up. By having the machine suspended in inverted position as shown in Fig. 2 the 45 possibility of breakage or damage is some-

what reduced. For instance, if some sharp pointed object, as a crowbar for example, were dropped upon the top of the box, it would have to penetrate the skid as well as the cover before any damage could be done 50 to the machine.

It is thus seen that this invention provides a strong and practical shipping box for the purpose above-described adapted to accomplish, among others, all of the objects and 55 advantages above set forth.

As many changes could be made in the above construction and many apparently widely different embodiments of this invention could be made without departing 60 from the scope thereof, it is intended that all matter contained in the above description or shown in the accompanying drawing shall be interpreted as illustrative and not 65 in a limiting sense.

It is also to be understood that the language used in the following claim is intended to cover all of the generic and specific features of the invention herein described and all statements of the scope of 70 the invention, which, as a matter of language, might be said to fall therebetween.

Having described my invention, what I claim as new and desire to secure by Letters Patent is:

In combination, a shipping box having a bottom and upright sides, interior supporting and reinforcing means on said sides adjacent the upper corners thereof, a member transversely supported on said means 80 from which a device to be shipped may be suspended, and means to cushion said member laterally and vertically.

In testimony whereof I affix my signature, in the presence of two witnesses.

EDWARD J. SHEEHAN.
